UNITED STATES PATENT OFFICE.

WILLIAM H. SMITH, OF LOS ANGELES, CALIFORNIA.

BOOK-HOLDER.

1,083,764.

Specification of Letters Patent.

Patented Jan. 6, 1914.

Application filed March 6, 1911. Serial No. 612,667.

To all whom it may concern:

Be it known that I, WILLIAM H. SMITH, a citizen of the United States, residing in the city of Los Angeles, county of Los Angeles, State of California, have invented new and useful Improvements in Book-Holders, of which the following is a specification.

My invention relates to a device for holding a book while a person is reading the same; and the object thereof is to provide a simple and efficient device which will hold a book in an open position so that a person lying upon a couch either upon his back 10 or on either side may be able to read the book without any undue strain upon the eye sight. I accomplish this object by the device described herein and illustrated in the accompanying drawings, in which,

20 Figure 1 is a perspective view of a bed with my improved reading device attached to one of the rails thereof. Fig. 2 is a side view of the parts shown in Fig. 1 provided with a standard for holding the same. Fig. 25 3 is an enlarged detail view of the book holding portion of the device and adjacent parts.

In the drawings 5 is a bed upon which the reader lies when perusing a book. On one side of the bed is secured clamp 6, which is 30 preferably removably attached to the bed. This clamp is provided with set screw 7 for adjustably securing standard 8, at any desired height in the clamp. This standard is preferably round so as to rotate in the 35 clamp, when desired. The upper portion of the standard is bent into U-shape and the short arm of the U terminates in a ball 9.

A pane of glass or panel 11 is provided with a frame 12. This frame is provided with 40 trunnions 13, the outer ends of which are screw threaded. Arms 14 and 15 have holes in their lower ends and are threaded on the trunnions and held in place by wing nuts 17, which also clamp the frame against rotation in the arms at whatever angle the 45 user desires to have it. The upper ends of these arms are formed into sockets which are in shape, the segment of a sphere, so

that they will fit upon a ball 9 and together with the ball form a ball joint. Just below 50 these sockets, when positioned for use, is a U-shaped clamping bolt 19, which passes through holes in the arms. One arm of the U is longer than the other and is threaded for the reception of a wing nut 20 by means 55 of which the arms may be clamped upon ball 9 to hold the frame in any position desired by the user.

When it is desired to use my device separate from the bed I provide a hollow column 60 24 preferably a piece of pipe, into which standard 8 is telescopically received. A set screw 21 holds the standard adjusted in the column. The column is provided with a base 22, which base has casters 23 so as to be 65 easily moved from place to place.

In the use of my device, the user will adjust the standard at such height as will bring the panel at the desired elevation 70 above his head when reclining upon the bed or couch. The panel will be adjusted by means of the wing nuts on the trunnions and the ball joint to bring the panel in a plane at right angles to the vision of the user and at the right focus from his eyes. The book 75 is then placed upon the panel with the page to be read thereon resting against the panel. If desired other supporting means for the book to be read can be used instead of the glass panel, such as wires extending across 80 the frame, but I prefer the use of a glass panel, as it is the simplest and best means of holding the book.

Having described my invention what I claim is:

A transparent panel adapted to support an open book placed thereon face downward, and means for adjustably supporting the panel above a reclining reader.

In witness that I claim the foregoing I have hereunto subscribed my name this 28th day of February, 1911.

WILLIAM H. SMITH.

Witnesses:

G. E. HARPHAM,

C. M. AUSTIN.
